MOTOR OPERATED BODY AND FACIAL MASSAGE BRUSH

Edward A. Irelan, Lombard, Ill., assignor to Sunbeam Corporation, Chicago, Ill., a corporation of Illinois

Filed July 1, 1968, Ser. No. 12,585

Term of patent 14 years

Int. Cl. D4—02

U.S. Cl. D4—14

FIG. 1 is a front perspective view of a motor operated body and facial massage brush;

FIG. 2 is a side elevational view thereof;

FIG. 3 is a rear elevational view thereof;

FIG. 4 is a top plan view thereof; and

FIG. 5 is a bottom plan view thereof.

The brush bristles shown in broken lines in FIG. 1 are for illustrative purposes only and form no part of the claim.

I claim:

The ornamental design for a motor operated body and facial massage brush, as shown and described.
